Robert C. M. Bowles
by Jas. H. LeFanchill
Atty.

UNITED STATES PATENT OFFICE.

ROBERT C. M. BOWLES, OF BOSTON, MASSACHUSETTS.

BINAURAL STETHOSCOPE.

SPECIFICATION forming part of Letters Patent No. 700,728, dated May 27, 1902.

Application filed March 5, 1902. Serial No. 96,804. (No model.)

To all whom it may concern:

Be it known that I, ROBERT C. M. BOWLES, a citizen of the United States, residing in Boston, in the county of Suffolk and State of Massachusetts, have invented an Improvement in Binaural Stethoscopes, of which the following description, in connection with the accompanying drawings, is a specification, like letters on the drawings representing like parts.

10 This invention relates to binaural stethoscopes, and has for its object to provide a combination instrument embodying the "bell" of the ordinary stethoscope and the diaphragm of the instrument shown and described in

15 United States Patent No. 677,172, granted to me June 25, 1901, whereby the two instruments are combined in one, so that the instrument can be converted substantially in an instant into either form of instrument to

20 be used in those cases for which it is best adapted.

Figure 1 is an elevation of a combination binaural stethoscope embodying this invention, and Fig. 2 an elevation of the same converted into a bell instrument.

In practicing auscultation it has been claimed that for most cases superior results are obtained with a binaural instrument employing the diaphragm-receiver, but that in

30 special cases—as, for instance, in listening over the apex of the lung for fine râles, (namely, in incipient phthisis) and for listening for superficial sounds, such as a friction rub of a presystolic murmur—superior results

35 are obtained by using the bell instrument, and to provide a single instrument which combines both forms in a simple and convenient manner and one which can be converted substantially in an instant from one form to

40 the other is the object of this present invention. For this purpose I employ the sound-receiving portion *a* of the instrument shown in the patent above referred to, which receiver is provided with the usual diaphragm

45 adapted to be applied to the person being examined and has the rigid sound-conducting tube *b*, and I connect the tube *b* with the bell *c* by means of a flexible tube *d* and a rigid tube *e*, which latter is inserted into the

50 mouth of the bell and is fitted tight in the opening through the bell. The remaining portion of the instrument may be of any suitable or usual construction, but preferably that herein shown, it consisting of the rigid ear-tubes *f*, connected together by the spring

g and joined by the flexible tubes *h* with the branches of the substantially Y-shaped rigid tube *i*, which is connected by the flexible tube *j* with the bell *c*.

From the above description it will be seen that when the instrument is assembled as shown in Fig. 1 the diaphragm-receiver *a* is used, and the said diaphragm by reason of the flexible tube *d* can be readily applied to the person to be examined without interfering with the transmission of the sound, whereas when it is desired to use the bell *c*—as, for instance, in the special cases above recited—the diaphragm-receiver can be disconnected by withdrawing the rigid tube *e* from the bell, whereupon the instrument is converted into the ordinary form of stethoscope, as shown in Fig. 2, which after being used can be instantly converted back into the diaphragm-receiver form of instrument shown in Fig. 1 by inserting the rigid tube *e* into the bell *c*. It will thus be seen that in the instrument shown in Fig. 1 both kinds of instruments are combined into a single instrument which is compact, conveniently assembled, and convertible substantially in an instant, thereby avoiding the necessity of the physician carrying two instruments in order to make any desired examination.

I claim—

1. A binaural stethoscope comprising a diaphragm-receiver adapted to be applied to the person to be examined, ear-tubes communicating with said receiver, and a "bell" forming part of the communication between said ear-tubes and said receiver, and detachably connected with the latter, substantially as described.

2. A binaural stethoscope comprising a diaphragm-receiver *a* provided with the rigid sound-conducting tube *b*, the "bell" *c*, a rigid tube *e* inserted into the mouth of said "bell" and detachably connected therewith, a flexible tube *d* connecting the rigid tube *e* with the sound-conducting tube of the receiver, and ear-tubes in communication with said "bell," substantially as described.

In testimony whereof I have signed my name to this specification in the presence of two subscribing witnesses.

ROBERT C. M. BOWLES.
